(57) **CLAIM**

The ornamental design for a cornhole board, as shown and described.

DESCRIPTION

FIG. 1 is a top perspective view of a cornhole board, showing my new design;

FIG. 2 is a top plan view thereof;

FIG. 3 is a left side elevation view, the right-side elevation view being a mirror image thereof, and

FIG. 4 is a bottom view thereof;

FIG. 5 is a side sectional view taken along lines 5-5 from FIG. 6 thereof;

FIG. 6 is a front elevation view thereof;

FIG. 7 is a rear elevation view thereof; and,

FIG. 8 is a top perspective exploded view.

The broken lines in the drawings depict portions of the cornhole board that form no part of the claimed design.

The indicia for the cross-sectional cut in FIG. 6 form no part of the claim.
